AUTOMATIC SHEET FEEDING APPARATUS

Thomas Shirley Foweraker, Bristol, England, assignor to E. S. & A. Robinson, Limited, Bristol, England, a company of Great Britain and Northern Ireland

Application October 16, 1939, Serial No. 299,651
In Great Britain October 17, 1938

3 Claims. (Cl. 271—62)

This invention relates to automatic sheet feeding apparatus intended more especially for association with printing and like machines although the invention is equally applicable to other machines where it is requisite that sheets should be fed singly from a pile which itself has to be constantly replenished.

In automatic sheet feeding apparatus heretofore constructed for feeding the top sheet of a pile of sheets by means of automatic separation and forwarding mechanism, the pile of sheets is generally carried on a table or board which is supported by a detachable framework or a set of lifting bars or other suitable mechanism attached to a series of four rising chains (hereafter called primary chains) which are caused to rise automatically by a picking device actuated by the top of the pile as the latter is rising, thus keeping the top sheet at a constant or approximately constant height relative to the automatic separating and forwarding mechanism. When each pile or load of sheets is used up, the table or board is disconnected from the lifting mechanism i. e. the framework or lifting bars and a new pile complete with table is wheeled or pushed into position.

The foregoing arrangement gives rise to considerable loss of time spent in exchanging an emptied pile table for a full one.

According to this invention a second set of four chains (hereafter called secondary chains) is combined with the sheet feeding apparatus which are caused to rise automatically by an independent picking device or a picking device common to both primary and secondary sets of chains and actuated in a similar manner, such secondary chains being capable of being used alternatively with the primary chains and carrying a pair of adjustable lifting bars or other suitable mechanism to support or carry loose laths or the like which are initially placed under each pile upon each table or board and project beyond the edges of each table or board and beyond the adjustable lifting bars mentioned above, and to be engaged therewith to take care of the end of the run of the pile of sheets whilst another pile of sheets is being placed in position and engaged with the primary chains.

In order that the invention may be clearly understood, reference is directed to the accompanying drawings, wherein:

Figs. 1, 2 and 3 illustrate diagrammatically automatic sheet feeding apparatus in accordance with the invention, and showing respectively three stages of operation.

In the drawings 1 indicates a pile of sheets from which the top sheet is taken by any known means of automatic separation and forwarding mechanism. The pile of sheets is carried on a table or board 2 which is supported by a set of lifting bars 3 connected to a series of four primary chains 4 which are caused to rise automatically by a picking device in the known manner, 5 indicates a set of four secondary chains which are associated with the sheet feeding apparatus and are caused to rise automatically by an independent picking device or a picking device common to both primary and secondary sets of chains may be employed. The secondary chains 5 are used alternatively with the primary chains 4 and carry a pair of adjustable lifting bars 6 which in turn support loose laths or the like 7 which are initially placed under each pile of sheets when the latter is put in position on the table 2 and so disposed as to project beyond the edges 20 of the table and beyond the lifting bars 6. The lifting bars 6 and the slats 7 take care of the continuation of the lift of the sheets while another pile of sheets is being placed in position and engage with the primary chains through the intermediary of the lifting bars 3.

The invention provides an arrangement whereby when a pile of sheets is nearly completely fed by the primary chains 4 the lifting bars 6 attached to the secondary chains 5 can be engaged with the laths 7 or the like and, after changing over from the primary picking device to the secondary picking device or switching over a single picking device common to both sets of chains, the remainder of the pile 1 can be continued to be fed sheet by sheet, during which time the empty table or board 2 can be lowered and exchanged for another table or board carrying a full pile.

Hand or motor driven devices are provided for raising or lowering either set of chains, and thus the top of the new pile can be raised into contact with the laths 7 or the like and be made to support the weight of the last remaining sheets of the first pile supported by the laths 45 or the like, after which the secondary picking device is disconnected and the primary picking device is again brought into action. The laths or the like are then withdrawn from under the few remaining sheets, which then rest in correct 50 position entirely on the new pile and automatic feeding continues in the ordinary manner until this pile is nearly completely fed and so on.

Preferably the four secondary chains 4 are arranged within the compass of the four primary 55

chains 5 and the lifting bars 3 of the primary chains 4 are arranged at right angles to the lifting bars 6 of the secondary chains 5, the laths 7 supported by the lifting bars 6 of the secondary chains being parallel with the lifting bars 3 of the primary chains.

It will be clearly seen from the above description that there is absolutely no time wasted in the changing of the piles and that automatic feeding from piles is therefore continuous and without break, because the whole of the operations of changing piles takes place whilst the automatic sheet feeder continues to function.

What I claim and desire to secure by Letters Patent is:

1. Automatic sheet feeding apparatus of the kind employing a set of lifting bars or other suitable mechanism attached to a series of primary chains wherein a set of secondary chains is combined with the apparatus and are caused to rise automatically by a picking device, such secondary chains being capable of being used alternatively with the primary chains and carrying a pair of adjustable lifting bars to support or

carry loose laths or the like which are initially placed under each pile upon each table or board and project beyond the edges of each table or board and beyond the adjustable lifting bars mentioned above, and to be engaged therewith to take care of the end of the run of the pile of sheets whilst another pile of sheets is being placed in position and engaged with the primary chains, the organization being such that the operation of the printing machine is continued while a new pile of sheets is being introduced into the sheet feeding apparatus.

2. Sheet feeding apparatus as claimed in claim 1 wherein the secondary chains are four in number and are arranged within the compass of four primary chains.

3. Automatic sheet feeding apparatus as claimed in claim 1 wherein the lifting bars of the primary chains are arranged at right angles to the lifting bars of the secondary chains so that the laths supported by the lifting bars of the secondary chains are parallel with the lifting bars of the primary chains.

THOMAS SHIRLEY FOWERAKER.
